UNITED STATES PATENT OFFICE.

CHARLES H. ALLEN, OF CHICAGO, ILLINOIS, ASSIGNOR, BY MESNE ASSIGNMENTS, TO THE ALLENLITE COMPANY, A CORPORATION OF ILLINOIS.

HEADLIGHT.

Application filed July 22, 1921. Serial No. 486,777.

To all whom it may concern:

Be it known that I, CHARLES H. ALLEN, a citizen of the United States, and a resident of the city of Chicago, in the county of Cook and State of Illinois, have invented certain new and useful Improvements in a Headlight; and I do hereby declare that the following is a full, clear, and exact description of the same, reference being had to the accompanying drawings, and to the numerals of reference marked thereon, which form a part of this specification.

This invention relates to improvements in headlights, particularly those adapted for use with automobiles or the like, but it will be evident that the same can be applied to any form of light designed to project parallel rays such as a search light or light house, or any other such device.

Another object of this invention is to provide adjustable means by which the direction of light from a lamp or deflector placed in any convenient position may be changed so as to project along the road at no great height above the roadway.

A further important object of this invention is the provision of a headlight which has an adjustable reflector made in sections so that the rays projected therefrom can be brought into any desired relation to each other by a simple adjustment of the different portions of the reflector, these reflecting sections being adapted to additionally illuminate the sides of the road.

A still further important object of this invention is the provision of a headlight for automobiles having means provided to eliminate the blinding glare common to such headlights and which glare often confuses an approaching driver resulting in accidents.

This invention is designed to so direct the rays of light issuing from the parabolic reflectors that they will not be thrown upwardly beyond a certain height, say about three or four feet, so that there will be no possibility of any of the rays entering the eyes of an approaching pedestrian or driver of another automobile.

It is furthermore an important object of this invention to provide a headlight so designed to direct the rays projected therefrom that the road in front of the automobile shall be perfectly illuminated for the convenience of the driver of the vehicle without

causing any annoyance to the drivers of approaching vehicles, it being a well known fact that in the ordinary headlight equipped with a parabolic reflector, the rays are not all parallel and some are diffused to quite a considerable angle and sometimes extend to quite a height above the road; and it will, moreover, be evident that if the light is all directed downwardly upon the road, the driver of the vehicle equipped with the light of this invention will be much less liable to any accident or bumps or jolts resulting from holes or obstructions in the road, which will be much more clearly visible.

Other and further important objects of this invention will be apparent from the disclosures in the accompanying drawings and following specification.

The invention (in a preferred form) is illustrated in the drawings and hereinafter more fully described.

On the drawings:

Figure 1 is a vertical sectional view of the improved headlight as contemplated by this invention.

Figure 2 is a front view of the assembled light.

Figure 3 is a sectional view of the headlight taken on the line 3—3 of Figure 1.

Figure 4 is a sectional view taken on the line 4—4 of Figure 1.

As shown on the drawings:

The reference numeral 10 indicates a casing in which the lamp and reflectors of the invention are placed. The casing 10 is provided with a circular opening in which a plate or lens 12 is fitted. Attached to the upper wall or top of the casing 10 is a downwardly extending parabolic reflector 14 as shown in Figures 1 and 3 within which is placed a globe or electric light 16 mounted in a suitable socket 18 fixed to the top of the casing 10. A reflector made in two curved portions 20 and 22 and hinged at 24 as shown in Figure 1 is placed immediately beneath the parabolic reflector 14 and is adapted to reflect the rays of light coming from the reflector 14 outwardly in front of the machine carrying the headlight and in a horizontal direction.

The hinge 24 has a pintle and is formed by four ears surrounding the pintle. Two of these ears 37 are integral with the mirror 22. The spaces 35 alternating with them serve to accommodate the ears 36 on the mirror 20, 110

while the spaces between the ears 36 accommodate the ears 37. Each of the ears 36 and 37 must stand, as shown in Figure 4, at a small angle with its mirror in order that the 5 pintle of the hinge shall be straight. The purpose of the hinge is to permit of an adjustment of the reflecting members 20 and 22 about such hinge relative to the casing 10, the reflector 14 and to each other. This 10 is accomplished by means of set screws or the like 26 and 28 which may be operated from the rear of the casing 10 by heads extending therethrough secured by lock nuts 32 as best shown in Figure 1. It is obvious 15 that the number of mirrors may be varied as desired.

It will be obvious that other ways of 20 hinging two curved mirrors together may be used and also that if desired, plane mirrors may be substituted. This construction, however, is preferred as it diffuses the light more efficiently and spreads the same in sort of a fan-like ray towards the sides of the road. It will further be evident that 25 only one side or half of each reflector need be made curved as shown, because the portion adapted to reflect the light outwardly towards the sides of the road only consists of one-half of the lens, namely, that half 30 upon the outer side of the lamp, which may be first on the left-hand side and then on the right-hand side, depending upon the side of the automobile to which the lamp is to be fixed.

35 It will be seen that by the use of the apparatus of this invention, all those rays which issue from the parabolic reflector 14 will be caused to project forwardly from

the lamp in a horizontal direction. This is accomplished by means of the reflectors 20 40 and 22, the position of which can be adjusted as required so as not to throw the light above a certain minimum height. The divergence of the rays is shown by the lines in Figure 1 which lines are of course exaggerated in order to show the construction 45 more clearly.

In the operation of this apparatus, a portion 50 of the light may be thrown upon the road at a distance between 20 and 200 feet 55 ahead of the car so as to make the surface of the road visible to the operator thereof, and the remainder of the light may be thrown by the other half of the reflecting means parallel to the road so as to illuminate objects a great distance ahead for additional safety in driving.

55 I claim as my invention:

In a head light structure, a casing, an incandescent lamp secured in one end of said 60 casing and projecting in a vertical plane, a parabolic reflector surrounding said lamp, a pair of curved deflectors having a common hinge, means for independently adjusting each curved deflector, said curved deflectors 65 being arranged at an angle to a vertical plane and a vertically arranged lens in said casing.

In testimony whereof I have hereunto 70 subscribed my name in the presence of two 75 subscribing witnesses.

CHARLES H. ALLEN.
